KNOCKDOWN TABLE

Erie J. Sauder, Archbold, Ohio

Application July 1, 1952, Serial No. 296,535

2 Claims. (Cl. 311—35)

1
This invention relates to knockdown furniture, and particularly to tables.

The object of the invention is the provision of a simple, strong and effective table of the knockdown type having leg members capable of easy and quick attachment to or detachment from the top member together with a bracing means for the legs which is sprung into engaging relation thereto and holds them in firm non-removable engagement with the top member and also serves to guide and rigidly brace the legs against relative lateral movements.

Further objects and advantages of the invention will be apparent from the following detailed description, and from the accompanying drawings illustrating one embodiment thereof and in which—

Fig. 1 is a perspective view of a table embodying the invention in set-up position;

Fig. 2 is an enlarged section on the line 2—2 in Fig. 1;

Fig. 3 is an enlarged perspective view of the engageable portions of a leg and the bracing member in separated relation;

Fig. 4 is a bottom perspective view of the top member of the table with one pair of legs fragmentarily shown and the cross member thereof engaged with the top member, and

Fig. 5 is a perspective view of one of the pairs of legs and the connecting cross member.

Referring to the drawings, 1 designates the top member of a table embodying the invention, 2 the four supporting legs therefor, and 3 the bracing member for the legs.

The top member 1 is preferably composed of a marginal frame 4 across the opening of which near its top edge is mounted a panel sheet 5 of some suitable stiff material and construction. The side members of the frame are provided at their inner sides adjacent to each end thereof and beneath the panel 5 with a vertical recess 6 that preferably has a restricted opening or neck portion at the inner side of the frame and is also open at its lower end. The recesses 6 are in pairs at each end portion of the top frame with the members of each pair in direct laterally opposed relation crosswise of the table top, as shown in Fig. 4.

The legs 2 are cross-connected in pairs at their tops by respective cross-braces 7 with the legs of each pair in mortised, recessed, or other suitable rigid connection with a respective cross-piece 7, so that the legs normally stand in one relation thereto but are capable of laterally flexing a limited extent toward and away from each

other. Each cross-piece 7 is provided at its ends with detent or mortised portions 8 complementary to and adapted to slidably fit into opposed recesses 6 in the top frame. The brace-bars 7 are capable of being freely engaged with or removed from the recesses 6 except when a canting pressure is applied thereto lengthwise of the table. The manner of engagement of the brace-bars with the frame sides also tends to strengthen the sides against relative lateral movements.

The leg bracing member 3 comprises two cross-pieces 10 rigidly spaced apart by one or more lengthwise extending strips 11, the length of which is suitable for positioning the cross-pieces 10 between the legs of the respective pair and at the same time to exert an outward pressure against each pair of legs lengthwise of the table. This applies a corresponding turning pressure to the associated cross-pieces 10 to cause a firm binding of the mortised portions 8 in the associated recesses 6. The cross-pieces 10 have studs 12 at their ends for fitting into respective recesses 13 in the opposed inwardly facing sides of the legs. The cross-pieces 10 are of a length slightly greater than the normal spacing of the legs of a pair, thus requiring an outward springing of the legs to permit an engaging of the cross-piece ends therewith. In Fig. 1, the normal position of the legs is shown in dotted lines and the outwardly sprung position is shown in full lines.

It is apparent that an assembling of the table parts is easily and quickly accomplished by first inserting the ends of the cross-pieces 7 of the two pairs of legs into the respective recesses 6 in the top frame, as shown at one end of Fig. 4, and then applying the leg brace 3 by inserting the studs 12 at the ends of its cross-pieces 10 into the respective leg recesses 13. In doing this, it is necessary to apply a spreading force on the legs of each pair so that the legs then exert an inward yielding holding force against the respective cross-pieces 10, and also to apply a slight outward turning force against each pair of legs to bind the tenons 8 of the leg cross-pieces 7 in the recesses 6. The table, when set up, is rigid and strong with its several parts attached without the use of screws, nails, or the like, thus permitting easy and quick assembly of the parts or a separation thereof for storage, packing or shipping.

I wish it understood that my invention is not limited to any specific construction, arrangement or form of the parts, as it is capable of numerous modifications and changes without departing from the spirit of the claims.

3

Having thus described my invention, what I claim as new, and desire to secure by United States Letters Patent, is:

1. In a knockdown table, a top having depending portions near its side edges adjacent to each end with vertical grooves therein in oppositely spaced relation, two pairs of legs each pair having a cross-piece connecting the upper ends of its legs, the cross-piece of each pair having end tenons for vertical insertion into the oppositely spaced grooves in the respective depending portions of the top and for binding engagement with the groove walls when the respective cross-pieces are outwardly canted, the legs of each pair being laterally springable from normal relation to the cross-pieces, and a brace frame connecting the pairs of legs intermediate their ends and having at each end a cross-piece disposed between and sprung into interengaging connection with the opposed legs of the respective pair whereby the pairs of legs are sprung outwardly lengthwise of the top and the legs of each pair are held in slightly outwardly spaced relation crosswise of the top.

2. In a knockdown table, a top having depending portions in its side edges adjacent to each end with vertical grooves therein in oppositely spaced relation, two pairs of legs each having a cross-piece connecting the upper ends of its legs, the cross-piece of each pair having end tenons for vertical insertion into the oppositely spaced grooves in the respective end portions of the top and for binding engagement with the groove walls when the respective cross-pieces are outwardly

canted, the legs of each pair being laterally springable from normal relation to the cross-pieces and each having intermediate its ends, on the side thereof facing the other leg, a horizontal cross recess extending outwardly from an inner edge and terminating short of the opposing edge to form a guide recess, each of said recesses having a laterally outwardly extending socket, and a brace frame connecting the pair of legs and having at each end a cross-piece disposed between and sprung into interengaging connection with the opposed legs of the respective pair, whereby the pairs of legs are sprung outwardly lengthwise of the top and the legs of each pair are held in slightly outwardly spaced relation crosswise of the top, each brace cross-piece seating in the recess of a respective leg when the brace is in leg bracing position.

ERIE J. SAUDER.
